BY J. Kaplan
ATTORNEY.

UNITED STATES PATENT OFFICE

JAMES S. MILLER, OF TRENTON, NEW JERSEY

CLAMP

Application filed February 1, 1930. Serial No. 425,267.

This invention relates to dental chairs and more particularly to an attachment for holding the paper towels which cover the head-rest of the chair.

5 The principal object of the invention is to provide a device of this nature for holding a towel used for covering a head-rest which can easily be attached to a dental chair without alteration thereof.

10 Another object of the invention is to provide a device of this kind having means for resiliently gripping a paper towel used for covering a head-rest which can be attached to any make of dental chair.

15 Other objects of the invention will appear as the disclosure progresses. It is obvious that the actual needs of manufacture may necessitate certain mechanical changes. It is therefore not intended to limit the invention to the embodiment illustrated but rather to define such limits in the appended claim. For a more general understanding of the invention attention is called to the drawing. In the drawing like reference characters 20 denote like parts throughout the specification.

Figure 1 is a side view of a dental chair with the device attached thereto.

Figure 2 is an enlarged side view of the attachment.

30 Figure 3 is a longitudinal cross section of the device.

Figure 4 is a top view of the attachment.

Figure 5 is a section on line 5-5 of Figure 4.

35 Figure 6 is a view of the paper towel.

Referring now to the drawing in detail, numeral 1 designates the dental chair and 2 a horizontal arm for supporting the head-rest 3. Fastened to the arm 2 is a clamp 4 for holding a paper towel 5 by the end 6. The body of the towel is adapted to cover the head-rest while the end 7 is adapted to curl underneath as shown in Figure 1 so it will not interfere with the patient's body.

40 The clamp 4 includes a support 8 having a rounded interior portion 9 which fits around one half the horizontal arm 2 and a hinged member 10 hinged on a pin 11. The member 10 also has a rounded interior portion 12 which fits around the other half of the

horizontal arm 2. For fastening the members together a wing nut 13 is provided.

Fastened to the support 8 at an angle is a clip 14 consisting of two gripping members 15 and 16 and a torsion spring 17 for normally holding the ends 18 and 19 of the gripping members together. As noted in Figure 3 the forward ends 18 and 19 of the clip are curved downwardly so as not to grip the paper towel too sharply at one point and thereby tear same. Also the sides 18' of the upper member extend downwardly and below the sides 19' of the forward end 19 of the lower member. Numeral 20 designates a pair of ears integral with the gripping member 15, and 21 a pair of co-operating ears integral with the gripping member 16. These ears are hinged on a pin 22 so that the ends 18 and 19 can be opened by pressing together the opposite ends.

It will thus be seen that I have provided a simple, inexpensive and efficient means for retaining a towel on a head-rest of a dental chair. The device can be attached without any alteration of the chair whatever and does not interfere with the work of the operator.

Having described my invention, I claim:

In a clamp of the class described, the combination of upper and lower members pivotally connected together, the forward end of the lower member being curved downwardly, the front and sides of the forward end of the upper member being curved downwardly, the said downwardly curved sides of the upper member extending below the sides of the said forward end of the lower member.

In testimony whereof I affix my signature.

JAMES S. MILLER.
